UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEAM FOR SEWED ARTICLES.

1,423,479.

Specification of Letters Patent.

Patented July 18, 1922.

Application filed August 4, 1917. Serial No. 184,448.

To all whom it may concern:

Be it known that I, ALBERT H. DE VOE, a citizen of the United States, residing at Westfield, in the county of Union and State 5 of New Jersey, have invented certain new and useful Improvements in Seams for Sewed Articles, of which the following is a specification, reference being had therein to the accompanying drawings.

10 This invention relates to seams for sewed articles and has for an object to provide a two-thread seam which may be formed without passing either of the thread-supplying masses through loops of the other thread 15 and which will possess great strength and marked non-raveling characteristics.

To this end the invention preferably comprises body-fabric material supporting a 20 row of well known single-chain stitches presenting longitudinally extending thread-portions at one side of the material and a 25 row of enchain loops at the other side of the material. A second thread extends preferably alongside the first thread and is 30 formed at intervals with loops which enter the material and embrace said enchain loops, preferably drawing portions of said enchain loops up into the material and binding or "snubbing" the limbs of said loops tightly together and to the material.

In the accompanying drawings Fig. 1 is 35 a perspective view of the preferred thread structure "in the air". Fig. 2 is a longitudinal section through the seam, in its preferred form. Fig. 3 is a bottom plan view of the same.

In the preferred embodiment of the invention illustrated, the seam comprises body fabric material presenting two superposed 40 plies 1 and 2. A main-thread 3 extends lengthwise of the line of seam at the face 4 of the material which, for convenience, may be called the upper face. The thread 3 is formed at intervals with the main-loops 5 45 having limbs 6 and 7 including vertical portions extending from the face 4 of the material through punctures 8 to the face 9 of the material which, for convenience, may be called the under face. The limbs of the 50 loops 5 further include portions 6' and 7' which extend along the under face of the material and terminate in a return bend embracing the limbs of an adjacent loop 5.

The thread is thus arranged in a connected series of enchain loops and, in the pres-

ent instance, forms a line of single-thread chain-stitches of well known construction and passing through the material. Such stitches are, per se, easily raveled out. To prevent easy raveling of the thread 3 and to 60 add greatly to the strength and symmetrical appearance of the seam I make use of an additional or auxiliary thread 9 which in the present instance, is formed into penetrative loops 10 extending into the same punctures occupied by the main loops 5 and embracing the limbs 6 and 7 of adjacent loops 5; preferably drawing the embraced portions of said loops into the material and 65 preferably tightly constricting the extremities of said loops 5 around the limbs 6 and 7 of adjacent loops 5, as shown in Fig. 3.

By virtue of this secure gripping of the loops 5 by the tightly constricted extremities of previously formed loops 5 and by the 75 loops 10, it will be appreciated that there will be little tendency for the seam to ravel and, indeed, if the seam is properly formed and well set, the thread 3 will often break before relative slippage of the limbs 6 and 7 80 of a loop 5 can be effected in an attempt to ravel out the seam. It will be seen that each loop 5 is, in the preferred embodiment, tightly gripped at two spaced points, to wit: at an intermediate portion by the constricted 85 extremity of a previously formed loop 5 and at its extremity by a loop 10 of the auxiliary thread which sets the extremity of the loop 5 tightly against or even draws it into the work, as shown in Fig. 2, tightly pressing or 90 "snubbing" the extremity of the loop 5 against the under face of the material adjacent the puncture 8.

Modifications of the invention will no doubt readily suggest themselves from the 95 above disclosure to those skilled in the art and I do not, therefore, intend the present invention to be limited to the exact structure shown and described.

Having thus set forth the nature of the 100 invention, what I claim herein is:—

1. A seam for sewed articles comprising body-fabric material and a line of stitches carried thereby and including a first thread formed into enchain loops and a second 105 thread presenting loops each entering the material and embracing an enchain loop at its point of connection with a succeeding loop to thereby tightly constrict said end around the succeeding enchain loop. 110

2. A seam for sewed articles comprising in combination, body-fabric material, a thread formed into a series of penetrative loops entering the material and another 5 thread formed into keying loops, each of said keying loops embracing another keying loop and being embraced at its point of connection with a succeeding loop by a penetrative loop, whereby the first-named keying 10 loop is drawn into the material and also tightly constricted around the second keying loop.

3. A seam for sewed articles comprising, body-fabric material, and two threads having 15 portions extending lengthwise of the line of seam at one face of the material and presenting penetrative loops extending into the same punctures in the material, each of said loops surrounding and being keyed by 20 another of said loops.

4. A seam for sewed articles comprising, body-fabric material and a line of stitches disposed in said material and including an auxiliary thread extending lengthwise of the 25 line of seam and formed into auxiliary loops, and a main thread extending lengthwise of the line of seam and formed into main loops, each of said main loops entering an auxiliary loop and embracing an 30 other main loop, a main and an auxiliary loop passing through each puncture in the material.

5. A seam for sewed articles comprising, body-fabric material, a line of single-thread 35 chain-stitches disposed therein and presenting a row of loops extending through needle-punctures in the material and enchainued at one face of the material, and a second thread extending along the opposite face of the 40 material and formed into loops entering the material and each of said loops embracing the end portion of an enchainued loop at one of said needle-punctures.

6. A seam for sewed articles comprising, 45 body-fabric, a main thread extending lengthwise of the line of seam and present-

ing penetrative thread-loop structures extending through the material, and an auxiliary thread formed into loops extending through the same punctures as the main 50 thread-loops, each of said penetrative thread-loop structures entering a loop of said auxiliary thread and embracing a loop of its own thread.

7. A seam for sewed articles comprising, 55 body-fabric material having punctures, a main thread having portions extending lengthwise of the line of seam at the upper face of the material and presenting penetrative main loops extending through said 60 punctures to the under face of the material and enchainued with one another to form single-chain stitches, and an additional thread having portions extending lengthwise of the line of seam at the upper face 65 of the material and presenting auxiliary penetrative loops extending into the punctures occupied by said main loops, each of said auxiliary loops embracing and being keyed by a main loop.

8. A seam for sewed articles comprising 70 fabric material, a line of stitches formed therein and including a first thread formed into enchainued loops, and a second thread having loops entering the material, each of 75 which embraces and tightly constricts one enchainued loop at its point of connection with a succeeding loop and tightly constricts the succeeding enchainued loop at an intermediate portion.

9. A seam for sewed articles comprising 80 fabric material, a line of stitches formed therein and including a primary thread having loops extending through the material, and a secondary thread having loops extending through the same punctures as the primary thread, each secondary thread-loop tightly constricting two primary thread-loops.

In testimony whereof, I have signed my 90 name to this specification.

ALBERT H. DE VOE.
